ORNAMENTAL LINK CHAIN

Eve Therese Lecoy, Beaumont, Calif.

Application June 3, 1955, Serial No. 36,351

Term of patent 14 years

(Cl. D45—16)

FIG. 2

Fig. 1 is a front view of an ornamental link chain embodying my new design;

Fig. 2 is a side view of the same. The broken line indicates that the design repeats itself in a vertical direction.

I claim:

The ornamental design for an ornamental link chain, substantially as shown and described.
